UNITED STATES PATENT OFFICE

WILFRED A. FINNEGAN, OF BANGOR, MAINE

KNOCKDOWN BOX

Application filed June 24, 1929. Serial No. 373,125.

This invention relates to knock-down boxes such as boxes used by children at play, and has for its object to provide a rectangular box, the body of which includes two side members and two end members, said members being separately connected by tongue and groove joints, the construction being such that, when the members are assembled, racking movements of the box tending to break the tongues and the walls of the grooves are opposed, and other desirable results are attained, the said members, and a bottom associated therewith, being adapted to be quickly assembled and separated.

15 Of the accompanying drawings forming a part of this specification,

Figure 1 is a perspective view of a sand-box body embodying the invention the bottom being removed.

20 Figure 2 is a perspective view of one of the side members.

Figure 3 is a perspective view of one of the end members.

Figure 4 is a horizontal section on the plane indicated by line 4—4 of Figure 1, showing the bottom.

Figure 5 is a section on line 5—5 of Figure 4.

Figure 6 is a fragmentary section on line 30 6—6 of Figure 4.

Figure 7 is a view similar to Figure 1, showing the box provided with legs.

Figure 8 is a fragmentary section on line 35 8—8 of Figure 7.

The same reference characters indicate the same parts in all of the figures.

The body of the sand-box is rectangular and comprises two duplicate side members 12, having outwardly projecting flanges 13, at 40 their upper edges, the ends of said flanges being offset inwardly from the ends of the side members, as shown by Figure 2, so that the side members include projecting extensions 12a, in which transverse dovetail grooves 14 are formed. The ends 13a of the flanges 13 constitute abutment shoulders, for a purpose hereinafter stated.

Said body comprises also two duplicate end members 15, having outwardly projecting flanges 16 at their upper edges, and dovetail

tongue 17 on their ends, removably inserted in the grooves 14, said flanges having end extensions 16a, which overhang the dovetail tongues 17, as shown by Figure 3, and bear on the upper edges of the extensions 12a of the side members to limit the insertion of the tongues in the grooves.

The shoulders 13a of the flanges 13 of the side members abut the inner edges of the flange extensions 16a of the end members, as shown by Figure 1, to oppose racking of the body and strains liable to break the tongues 17 and the walls of the grooves 14, the side and end members, and in fact, all of the parts of the box, being preferably made of wood, so that there is a possibility of breakage of the tongues and grooves by racking strains.

While the body may be used without a bottom, it is desirable to provide one. I therefore provide the body with bottom-supporting means, and include in the construction of the box a bottom removably supported by said means. The bottom, in this instance, is composed of a plurality of loose boards 20, shown by Figure 4. The meeting edges of 70 said boards preferably have the zigzag formation shown by Figure 6, to prevent leakage of sand between the boards. It is obvious that the bottom may be formed in one piece, if desired.

I prefer to support the bottom by the cleats next described. The side members 12 are provided at their lower edges with inwardly projecting cleats 21, whose ends are offset inwardly from the ends of the side member extensions 12a, and from the grooves 14, therein, as shown by Figure 2. The end members 15 are provided at their lower edges with inwardly projecting cleats 22, whose ends are offset inwardly from the dovetail tongues 17, as shown by Figure 3. The outer sides of the end member cleats 22 are arranged to abut the ends of the side member cleats 21, as indicated by Figure 1 and by dotted lines in Figure 4, to additionally oppose racking of the body and breakage of the tongues and grooves. The bottom bears 80 separably on the cleats, so that it may be easily removed. It is obvious that the cleats 85 may serve only to prevent racking of the

body, no bottom being provided, the box body bearing on the ground or a floor.

Figures 7 and 8 show a sand box embodying the construction above described and provided with legs adapted to support the box suitably raised, the legs being separably connected with the box body. Two opposite members of the body, preferably the side members 12, are provided with sockets 25, formed to receive legs 26. Said legs have reduced upper portions removably inserted in the sockets, and larger lower portions, the upper ends of which form shoulders 27 (Figure 8) bearing on the lower edges of the side members 12, to support the weight of the box.

The inner edges of the flanges 13 and 16 are preferably flush with the inner sides of the side and end members, so that said flanges form an open mouth portion of the storage space, said portion being of the same area as the portion formed by the side and end members, and permitting unobstructed access to all portions of said storage space, and removal of all of the sand therefrom by pouring when the box is inverted.

I claim:

1. An open knock-down sand box, comprising a pair of side members, having end extensions containing vertical dovetail grooves, and outwardly projecting flanges, fixed to the upper edges of said members, the ends of said flanges forming abutment shoulders from which said extensions project, and a pair of end members having vertical dovetail tongues on their ends removably inserted in said grooves, and outwardly projecting flanges fixed to their upper edges, said flanges having extensions overhanging said tongues and bearing on the extensions of the side members to limit the entrance of the tongues into the grooves, and on the abutment shoulders of the side members, to oppose racking of the box, the inner edges of said flanges being flush with the inner sides of the side and end members, so that said flanges form an open mouth portion of the storage space, said portion being of the same area as the portion formed by the side and end members, and permitting unobstructed access to all portions to said storage space.

2. An open knock-down sand box, comprising a pair of side members, having end extensions containing vertical dovetail grooves, and outwardly projecting flanges, fixed to the upper edges of said members, the ends of said flanges forming abutment shoulders from which said extensions project, and a pair of end members having vertical dovetail tongues on their ends removably inserted in said grooves, and outwardly projecting flanges fixed to their upper edges, said flanges having extensions overhanging said tongues and bearing on the extensions of the side

members to limit the entrance of the tongues into the grooves, and on the abutment shoulders of the side members, to oppose racking of the box, the side members being provided at their lower edges with inwardly projecting cleats, whose ends are offset inwardly from the vertical grooves, while the end members are provided at their lower edges with inwardly projecting cleats, whose end portions abut the end portions of the side member cleats to additionally oppose racking of the body.

In testimony whereof I have affixed my signature.

WILFRED A. FINNEGAN.
